(57) **CLAIM**

The ornamental design for a grip for a sporting implement, as shown and described.

DESCRIPTION

FIG. 1 is a right, top perspective view of a grip for a sporting implement showing a first embodiment of the new design;

FIG. 2 is a right, bottom perspective view of the new design shown in FIG. 1;

FIG. 3 is a front view of the new design shown in FIG. 1;

FIG. 4 is a rear view of the new design shown in FIG. 1;

FIG. 5 is a left side view of the new design shown in FIG. 1;

FIG. 6 is a right side view of the new design shown in FIG. 1;

FIG. 7 is a top view of the new design shown in FIG. 1;

FIG. 8 is a bottom view of the new design shown in FIG. 1;

FIG. 9 is a right side view of the new design shown in FIG. 1, identical to FIG. 6, but including section lines 10-10,

11-11, 12-12, and 13-13;

FIG. 10 is a cross-section view taken along lines 10-10 of FIG. 9;

FIG. 11 is a cross-section view taken along lines 11-11 of FIG. 9;

FIG. 12 is a cross-section view taken along lines 12-12 of FIG. 9;

FIG. 13 is a cross-section view taken along lines 13-13 of FIG. 9;

FIG. 14 is a right, top perspective view of a grip for a sporting implement showing a second embodiment of the new design;

FIG. 15 is a right, bottom perspective view of the new design shown in FIG. 14;

FIG. 16 is a front view of the new design shown in FIG. 14;

FIG. 17 is a rear view of the new design shown in FIG. 14;

FIG. 18 is a left side view of the new design shown in FIG. 14;

FIG. 19 is a right side view of the new design shown in FIG. 14;

FIG. 20 is a top view of the new design shown in FIG. 14;

FIG. 21 is a bottom view of the new design shown in FIG. 14;

FIG. 22 is a right side view of the new design shown in FIG. 14, identical to FIG. 19, but including section lines 23-23,

24-24, 25-25, and 26-26;

FIG. 23 is a cross-section view taken along lines 23-23 of FIG. 22;

FIG. 24 is a cross-section view taken along lines 24-24 of FIG. 22;

FIG. 25 is a cross-section view taken along lines 25-25 of FIG. 22; and,

(Continued)

FIG. 26 is a cross-section view taken along lines 26-26 of FIG. 22.

The broken lines in the drawings depict environment, or portions, of the grip for a sporting implement that form no part of the claimed design.
